(57) **CLAIM**

The ornamental design for a gusseted flexible bottle, as shown and described.

DESCRIPTION

FIG. 1 is a perspective view of a gusseted flexible bottle in accordance with a first embodiment of the ornamental design of the present invention, showing the gusseted flexible bottle in a filled state.

FIG. 2 is a side view thereof, the opposite side view being a mirror image.

FIG. 3 is front view thereof.

FIG. 4 is rear view thereof.

FIG. 5 is a top view thereof.

FIG. 6 is a bottom view thereof.

FIG. 7 is a perspective view of the gusseted flexible bottle, shown in an empty state.

FIG. 8 is a front view thereof.

FIG. 9 is a side view thereof, the opposite side view being a mirror image.

FIG. 10 is a top view thereof.

FIG. 11 is a bottom view thereof.

FIG. 12 is a perspective view of a gusseted flexible bottle in accordance with a second embodiment of the ornamental design of the present invention, showing the gusseted flexible bottle in a filled state.

FIG. 13 is a side view thereof, the opposite side view being a mirror image.

FIG. 14 is front view thereof.

FIG. 15 is rear view thereof.

FIG. 16 is a top view thereof.

FIG. 17 is a bottom view thereof.

FIG. 18 is a perspective view of the second embodiment of the gusseted flexible bottle, shown in an empty state.

FIG. 19 is a front view thereof.

FIG. 20 is a side view thereof, the opposite side view being a mirror image.

FIG. 21 is a top view thereof; and,

FIG. 22 is a bottom view thereof.

Broken lines in the figures are for illustrative purposes only and form no part of the claimed design. Specifically, dashed lines define unclaimed features, and dot-dash lines define boundaries of the claimed design.
